UNITED STATES PATENT OFFICE.

BERNARD W. DOYLE, OF LEOMINSTER, MASSACHUSETTS, ASSIGNOR TO PACIFIC NOVELTY COMPANY, A CORPORATION OF NEW YORK.

DESIGN FOR A COMB.

No. 39,657.

Specification for Design.

Patented Nov. 3, 1908.

Application filed June 10, 1908. Serial No. 437,765. Term of patent 14 years.

● *To all whom it may concern:*

Be it known that I, BERNARD W. DOYLE, a citizen of the United States, residing at Leominster, in the county of Worcester and State of Massachusetts, have invented a new, original, and ornamental Design for a Comb, of which the following is a specification, reference being had to the accompanying drawing, forming part thereof.

Figure 1 is a plan view of the design for a comb, and Fig. 2 is a perspective view of the same.

The design consists of a body or main portion formed as a cylindrical narrow band or broken ring *a*, and a series of teeth *b* extending as a continuous row from the whole

length of one edge of the body *a* and bent to lie substantially in a plane at right angles to the axis of the cylindrical body, and radially arranged or converging towards said axis.

The inner ends of the teeth project directly from the edge of the body and by easy right angle bends *c* pass from the body into the plane transversely disposed to the axis of the said cylindrical body.

I claim.

The ornamental design for a comb, as shown and described.

BERNARD W. DOYLE.
